(57) **CLAIM**

The ornamental design for dispensing closure with raster-shaped valve support pin, as shown and described.

DESCRIPTION

3. Dispensing closure with raster-shaped valve support pin

3.1: Perspective view with the closure in an opened position

3.2: Enlarged partial view of the raster-shaped valve support pin shown removed from the dispensing closure for clarity of disclosure

3.3: Perspective view with the closure in a closed position

In the reproductions, the broken lines show portions of a dispensing closure that forms no part of the claim.
